UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

SPUR-HOBBLING MACHINE.

Application filed August 27, 1924. Serial No. 734,487.

This invention deals with hobbing-machines and it undertakes so to improve upon the mechanism of my prior U. S. Patent No. 1,472,767, that the principles of construction 5 thereof may be carried forward and utilized in an even more simple, rigid and sturdy manner, and at the same time render available a machine exhibiting various conveniences in point of an invariable location of 10 the work, in respect to the manipulability of the control levers, in regard to safety interlock elements, etc.

In conjunction with the foregoing objectives, this invention contemplates means for 15 enabling the cutter and the work to be quickly brought nearly into the tooling relation, and for enabling the tooling operation thereupon to be brought into action at the slower 20 rate appropriate to the capacity of the cutter; the system embracing certain interlocking controls in the nature of safety characteristics to guard the user against causing damage through errors in judgment, improper manipulations or neglect, 25 and also to enable the user quickly to terminate the tooling operation and quickly to withdraw the cutter from the work in case 30 the action requires correction. Thus, when the cutter is normally feeding into the work, or when it is partly in the blank and the feed 35 has been discontinued, it is not possible for the user (by the mere manipulation of any single lever) to impart a downward rapid traverse to the cutter in these circumstances 40 and thereby cause damage. On the other hand, the cutter may at all times be withdrawn quickly from the work for purposes 45 of inspection or correction. Again, to guard against simultaneously feeding both the cutter and the stanchion, there is provided an 50 interlock between the respective levers that control those functions. Other safety features will be pointed out hereinafter.

To afford greater facility in the manipulation 45 of the machine, this invention contemplates various conveniences in the operative elements thereof. For example, it is not necessary that the cutter shall be rotating 55 in order to utilize the means for accomplishing a power traverse since the latter may be resorted to either while the cutter spindle is idle or in operation. This and other characteristics of convenience will be

explained in detail in connection with the drawings which typify one embodiment of 55 the features characteristic of this invention, and in such drawings:

Fig. 1 is a side elevation of a hobbing-machine showing a fixed work spindle and a shiftable stanchion supporting a head slid- 60 able thereon which carries the hob spindle. Fig. 2 is a plan and Figs. 3 and 4 are rear and front end elevations of the machine. Fig. 5 is a skeleton of the transmission system and control levers for performing the 65 various movements of the working and positioning elements of the machine. Fig. 6 is a sectional detail of a friction coupling between the prime-mover and a part of the transmission system. Fig. 7 is a side eleva- 70 tion in detail of a portion of the interlocking control system for the quick traverse and feed for the hob-carrying head. Fig. 8 is a condensed fragmentary side-elevation of the means actuated by the cutter-slide for 75 automatically operating the manually-operable levers for controlling the feed and the quick-traverse. Fig. 11 is an end-elevation of said levers. Fig. 9 is a detail of the spring snap clutch for throwing in and out 80 the feed transmission. Fig. 10 is a detail of the spring-detent for urging the feed hand-lever into either one or the other of its alternative positions.

The bed A, in this embodiment, is elongated and positioned horizontally and provides a forward working region in which the work spindle is directly journaled so as to occupy a fixed position, and the bed provides also a rear mechanism supporting 90 region on which the stanchion is slidably mounted. The work spindle W is shown journaled in a fixed bearing A' and it extends downwardly into the interior of the bed as indicated by W' and, at its lower end, 95 carries a worm-wheel W² by which it is driven. The portion of the bed that houses the worm-wheel W² is appropriately enlarged to contain that wheel and, inasmuch as the wheel occupies a fixed position in 100 space, the bed admits of being ribbed and reinforced closely to the wheel and thus made very rigid as will be understood without illustration. It is noteworthy that by thus giving the work spindle a fixed position 105 at the forward end of the bed, it is at all

times quickly accessible to the user and it is not at one time further from the end of the bed than at another as often happens when the work spindle is shiftable in position. 5 The mounting of the spindle is accomplished in a very solid manner with the object of realizing the effect of an anvil so that it virtually supports the work substantially as solidly as though it was clamped to the bed 10 itself and, in consequence, the tendency to vibrate and chatter is reduced to a minimum.

The stanchion S is in the nature of a heavy box-like casting which is provided with slideways S' and S² at right angles to 15 one another; the slideways S' resting on the slideways S³ provided by the surface of the bed and arranged to permit the heavy stanchion to be slid towards and away from the axis of the work spindle for the purpose of 20 determining the diameter of the gear G to be cut by the machine. The purpose of the transverse slideways S² is to support and guide a head H which is thus shiftable parallel with the axis of the work-spindle so that the 25 cutter or hub (which is carried by the head) may in the course of the feeding movement cut the teeth of the gear G. It will be understood that this head H is suitably gibbed to the slideways S² and, in order to 30 counterbalance the weight of the head H, a counterweight H⁴ may be arranged to rise and descend in an appropriate well provided by the stanchion S; conventional ropes and 35 pulleys H² and H³ being provided as will be understood.

It is to be noted that the stanchion, being 40 heavy and massive, is in effect a part of the solid bed itself because when clamped down to that bed, it becomes very solid therewith owing to the action of the clamps augmented by the weight of the stanchion and by reason 45 of the fact that the base of the stanchion S is very extensive so as to resist effectively such overturning forces as result from the pressure of the hob against the work during 50 the tooling operation. It will likewise be noted that the stanchion requires to be shifted only when a change is to be made in the diameter of the gears being cut which ordinarily 55 would be quite infrequent and it will also be noted that the shifting of the stanchion does not reduce the facility of access of the user to the work spindle and does not interpose obstructions when brought closer to that 60 spindle. It will also be noted that the slide-ways S' at the base of the stanchion runs to a region substantially underlying the head H so that this construction avoids the 65 objectionable overhang which is necessitated whenever the work spindle is mounted on a carriage which slides on the bed.

The transmission system for rotating both the work spindle and the hob, and for progressively feeding the head H, and for shifting 70 the position of the stanchion S, and for

varying the rates of rotations and for shifting the parts quickly or slowly as the case may be, will now be described.

This transmission is in the nature of a balanced drive and comprehends an intermediate splined shaft X and two main transmission shafts Y and Z; shaft Y being also splined. These two shafts are disposed at right angles and the intermediate shaft is parallel with one of them; the latter being in this embodiment the shaft that communicates motion to the work spindle. The intermediate shaft receives the power in the first instance; this being accomplished by the power line consisting of a pulley P or other prime mover, the power shaft P' and appropriate gears such, for example, as the two spur gears P² and P³ and the two angle gears P⁴ and P⁵. The splined transmission shaft Y is journaled in the shiftable stanchion so as bodily to travel therewith and at its lower end is provided with an angle gear y which meshes with an angle gear x' which is splined to the intermediate shaft X. The cutter C is mounted on a spindle c 75 which is journaled in the head H at a fixed angle sloping either to the right or to the left as shown by Fig. 4. This angle may be in the neighborhood of five degrees for a single thread hob or ten degrees for a double thread hob. This angle being fixed and not of great magnitude admits of a very simple driving connection between the spindle c and the splined transmission shaft Y. That is to say, a worm y' is splined to the shaft Y 80 which is journaled in the head H so that as the head moves up or down, the worm will be correspondingly shifted on the shaft Y and a worm-wheel c' is affixed to the spindle c and its teeth are so cut that the meshing 85 will be perfect although the worm and worm-wheel are at an angle to each other.

The other non-splined transmission shaft Z is journaled in the bed of the machine and has a worm z' affixed thereto for driving 90 the spindle W through the worm-wheel W'. The pair of change gears x² and z² establish the driving relation between the intermediate power shaft X and the transmission shaft Z; it being observed that this arrangement 95 provides a balanced drive in which the four gears W², z', z² and x² transmit the motion to the work spindle, and likewise four gears c', y', y and x' transmit the motion 100 to the cutter. Further details will be described in connection with an explanation of the manipulations of the machine.

To start the machine the power lever B is actuated. This shifts the collar 8 and slides a long key 9 (which is translatable counter-sunk in the shaft P') and this key 105 actuates a suitable clutch (not shown) between the prime mover P and the shaft P'. The transmission elements previously described are then maintained in motion by the 110

power and the cutter and the work are both revolving at the relative rate determined by the two change gears z^2 and x^2 .

To shift quickly the stanchion the lever U is manually actuated and this shifts the link U^2 lengthwise and accomplishes two things, i. e., it throws out the clutch F^7 and isolates the shaft F^6 (which transmits feeding motion to the spindle head) so that all such feed is discontinued, and it also throws in the clutch S^8 to enable motion to be transmitted from the gear S^9 to the gear S^7 . The feed-discontinuing clutch F^7 is shifted by a lever U^4 and the stanchion-actuating clutch S^8 is shifted by a shoe U^3 on the link U^2 . With the parts in the position described, the stanchion may be shifted quickly by power either towards the work or away from the work or not at all; depending upon the position of the hand lever a shown in detail by Fig. 11. Fast to the pulley P is a gear Q which permanently meshes with a gear Q' which is frictionally connected through the leather facings 17 and 18 of the clamp disks 19 and 20 with the shaft Q^2 ; a nut 21 serving to determine the amount of the friction. In this manner, the shaft Q^2 is driven simultaneously with, but impositively by, the pulley P so that slippage may occur and breakage prevented in case the stanchion be brought against some obstacle. On the end of the shaft Q^2 is a bevel gear Q^3 which permanently meshes with the right and left bevel gears Q^4 and Q^5 which are loosely mounted on the shaft Q^7 . A clutch Q^6 is splined to the shaft Q^7 and when shifted to the one side or the other will cause that shaft to rotate either one way or the other; or not at all if the clutch Q^6 be in neutral position. The position of the clutch is determined by a finger e projecting from a lever on the rock-shaft d which, through the bevel gears c and c' , is actuated by the rock-shaft b which is rocked by the hand-lever a . On the shaft Q^7 is affixed a gear Q^8 which drives a gear S^9 and (when the clutch S^8 is connected) the drive is communicated to the gear S^7 and the gear S^6 is thus rotated. That gear is in turn splined to the screw S^5 which runs through the fixed nut N and causes the screw to translate bodily; this translation being communicated to the stanchion by means of an appropriate lug or part S^4 journaled to the screw. In this manner, the stanchion is quickly traversed by power to the right or to the left as the case may be.

To manually shift the stanchion a hand-wheel V (provided with graduations or micrometer adjustments) is affixed to a shaft that carries an angle gear V' which meshes with an angle gear V^2 which is splined to the screw S^5 and enables it to be turned by hand. The above described quick traverse in conjunction with the manual means en-

ables the user very readily to bring the stanchion to any desired position with respect to the work-spindle for cutting spur-gears or certain helical gears of predetermined diameters.

To feed the stanchion the shaft Q^7 is driven at a slower rate by means which will now be described. This feeding of the stanchion is employed when it is desired to cut worm gears as distinguished from spur or helical gears. The feeding motion is conveyed by a transmission consisting of an angle gear 1 mounted on the shaft Z and meshing with an angle gear 2 affixed to the shaft 3. A worm 4 on that shaft drives a worm-wheel 5 which turns the shaft 6 through appropriate change-gears designated generally by 7. The gear r^2 is driven and this gear is affixed to a sleeve r which is loosely mounted on the shaft Q^7 but may be connected thereto by the clutch-teeth r' . A shifter pin p may bodily shift the sleeve r to establish or disconnect the parts described; this shifter pin being loosely mounted on the shaft o . A yieldable detent p' acts on the shifter pin so as to urge the parts into clutching relation; the purpose being to provide a quick yet not too positive an action. Bevel gears n and n' connect the shaft o with a rock-shaft m and a hand-lever k permits the rock-shaft m to be moved manually. On this rock-shaft m is a small arm m' which has a spring-pressed pawl 22 cooperating with an oscillatable pawl m^2 . The latter by moving against either the stop-pin 23 or the stop-pin 24 will resiliently determine the position of the rock-shaft m and this motion will be correspondingly imparted to the rock-shaft o which carries the part p^3 provided with the aforesaid yielding detent p' to throw the sleeve clutch r impositively into operative position and provided also with the lug p^2 to throw it positively out. Thus it will be seen that if the hand-lever a be set in neutral position so that the quick traverse transmission is out of action, and if the hand-lever k be set in position to connect the gear Q^8 with the feeding transmission, then will the stanchion be caused to feed (if the hand-lever U is "in") and the action will be appropriate for the cutting of the teeth of worm-wheels. Interlocking means, which will be explained subsequently, prevent the user from connecting simultaneously the feeding and the quick traverse transmissions with either the stanchion or the cutter supporting head.

To feed the cutter head the parts will be brought into the positions and relations last described for feeding the stanchion with the exception that the hand-lever U is thrown "out". This disconnects the clutch S^8 so that the gear S^9 is isolated and runs idly. When the clutch S^8 is disconnected, the

clutch F^7 is engaged with the result that the shaft F^6 is connected to the shaft Q^7 and runs at the same rate which, as has been explained, is determined by the feed change-gears designated generally by 7. Angle gears F^5 and F^4 transmit the motion to the shaft F^3 which is journaled in the stanchion and, at its upper end has a gear F^2 which meshes with a gear F' which is a unit with a nut that turns about the non-rotatable feed-screw F . That feed-screw is affixed to the head H and is caused to move up or down, as the case may be, by the rotating nut and, in this manner, the cutter journaled on the head H is caused to feed downwardly whenever the parts are connected up as described, or to make a quick traverse either up or down when the parts are differently connected as will be described.

To shift quickly down the cutter head, the lever a must be moved down into the lower dotted position shown by Fig. 11. Before this can be done, the block pin g must be pulled against its spring out of the path of that lever. This temporary obstruction is precautionary so that the user will be obliged deliberately to perform an extra operation to bring the head down rapidly; otherwise he might inadvertently press down the lever a and cause the cutter to be brought down rapidly into the work and broken. From what has been said heretofore, it will be seen that this depression of the lever a connects the shaft Q^7 with a high speed transmission and, since that shaft may also be connected with a low speed transmission, it is essential that the one shall be out before the other can come in and conversely. This safeguarding is accomplished by the interlock shown by Fig. 11 in which the hand-lever k that controls the connection of the slow motion transmission (the feed) has an arm k^2 provided with a V-shaped finger f which (when the feed is "on") enters a central recess in the ledge a^2 of the lever a . When, however, the lever a is not in its neutral position, the finger f will, by reason of its double slope, be forced out of the recess and caused to ride on the higher portions of the ledge a^2 and this can only happen when the feed-lever k is in the dotted position indicated by Fig. 11. In other words, when clutch Q^6 is in either its right or its left engaging position, clutch r' is disconnected, and when clutch r' is engaged, clutch Q^6 can be only in its neutral non-transmitting position. Therefore, by pulling out pin g and by depressing the lever a , the feed is disconnected and the quick traverse is accomplished and the head H moves down rapidly; providing, of course, that the hand-lever U is in such a position that the clutch S^8 which moves the stanchion is disconnected and the clutch F^7 which moves the cutter head is engaged.

To shift quickly and upwardly the cutter head, the lever a is raised to the upper dotted position shown by Fig. 11. The interlock again insures that the feed will be out so that when the clutch Q^6 is moved into its motion reversing position, the transmission will take place through the quick traverse means and the head will go up rapidly.

To adjust the limits of travel of the stanchion, on both of the rock-shafts m and b are dogs which may be adjustably affixed in any desired position lengthwise on those shafts. As shown by Fig. 8, dogs 25 and 26 are on the rock-shaft b and these dogs have bevel contact surfaces which may engage either one or the other of the pins 27 and 28 whenever the box S^8 (which is a part of the stanchion) moves sufficiently to the right or to the left to engage either one or the other of those dogs. The engagement effects a rocking of the shaft b to bring the hand-lever a to its neutral position and to render idle the clutch Q^6 and thus arrest automatically the travel of the stanchion. Likewise, if the stanchion be "feeding", a dog 29 on the rock-shaft m will be engaged by the pin 30 and that shaft will be rocked to move the feed lever k upwardly into its neutral position which means that the clutch r' will be disengaged and the stanchion will cease to feed. The mechanism therefore provides safeguards against any lack of attention on the part of the user when the stanchion is being traveled either rapidly or slowly.

To adjust the limits of the "quick traverse" travel of the cutter head, this invention provides a shift-rod T pivoted to the free end of an arm 31 extending to the right (as shown by Fig. 11) from the pivot of the hand-lever a so that, when lever a is depressed, the shift-rod T will rise, and conversely. Hence if said rod T be pushed down, the effect will be the same on the control mechanism as if the user had pulled up the hand-lever a .

Now, adjustably bolted (by slot 10 and bolts 11) to the cutter-head H is a cam-plate D . This has an inclined face 12 and into the path of travel of that face will be (when the quick down traverse is on) the finger 16 on the end of the lower arm of a bell-crank lever E which has a fixed pivot at 15. The shift-rod T is pivoted at its upper end 14 to the other arm of that bell-crank lever. Hence, when the shift-rod is raised (to produce a quick down-traverse) the finger 16 will be in the path of the cam-plate D . If now the cutter-head descends, the inclined face will in due time contact with the finger 16 and depress the shift-rod T ; thus raising the hand-lever a .

But this automatic raising of the hand-lever a (corresponding to a depression of

the shift rod T) will cease as soon as the inclined face 12 has passed the finger on the bell-crank lever E. It is to be noted that the extent of this movement is such that, 5 when the finger is coincident with the flat non-sloping face 13 of the cam-plate D, the hand-lever *a* is in its mid-position as shown in full lines by Fig. 11. Hence the detent *f* of the feed hand-lever *k* will now be able

10 (when actuated by the user) to enter the notch in the surface *a*² and the down-feed of the cutter-head will be substituted for the down quick-traverse. The cutter is now about to enter the work at a "feed" rate 15 only and cut the gear-teeth. If now the user should try, through a mistake, to push down the hand-lever *a*, he would be prevented by the finger 16 which is now riding along the non-sloping face 13. Therefore, 20 the down quick-traverse is limited (by adjusting the initial position of the cam plate D), and the user cannot commit the error of causing the cutter to enter the work at any rate faster than that of the normal 25 "feed".

To adjust the limit of the upward quick-traverse, the collar or dog T² is set at the appropriate point on the rod T so that the projection H (affixed to the cutter-head) 30 will engage said collar and move the traverse rod T upwardly and thereby depress the hand-lever *a* from its raised into its neutral position. This will stop the travel of the cutter-head H because the detent shown by 35 Fig. 10 will hold the hand-lever *k* in the dotted line position shown by Fig. 11 until it is actuated by hand.

To limit the extent of feed there is an adjustable collar 33 on the feed shift-rod 34 40 which controls the position of the hand-lever *k* as will be understood. Also, as a matter of precaution, collars T', 36 and 37 are permanently affixed to the respective rods T and 34 to prevent the user from making any adjustments beyond the maximum 45 scope of travel provided for the cutter head H.

It may be noted, in regard to the control system, that the automatic throw-out of the 50 feed when the quick-traverse is thrown in to elevate the cutter-head makes it easy for the attendant to check carefully the progress of the cutting operation. Thus, to measure the depth of cut or the thickness of a tooth, 55 the attendant merely needs to elevate the power-traverse lever and the cutter-head will forthwith quickly rise. The attendant does not, therefore, have to first operate a feed-lever to throw out the feed, and then 60 to operate the quick-traverse lever, but merely the latter alone.

Without further analysis, the foregoing will so fully reveal the gist of this invention that others can, by applying current 65 knowledge, readily adapt it for various

utilizations by retaining one or more of the features that, from the standpoint of the prior art, fairly constitute essential characteristics of either the generic or specific aspects of this invention, and, therefore, 70 such adaptations should be, and are intended to be, comprehended within the meaning and range of equivalency of the following claims.—

Having thus revealed this invention, I 75 claim as new and desire to secure the following combinations and elements, or equivalents thereof, by Letters Patent of the United States:

1. A hobber combining a head; a quick- 80 traverse mechanism; a manual control normally available for causing said mechanism quickly to traverse said head in either of two opposite directions; and an interlock positionable by said head when adjacent a 85 predetermined zone to prevent said control from being so actuated as to cause said head to enter said zone at a quick traverse rate.

2. A hobber combining a head; means for feeding it in a given direction; a quick- 90 traverse for shifting it in opposite directions; a feed-lever; a traverse lever; and a member shiftable into a position preventing said quick-traverse from operating said head in said given direction but not in an 95 opposite direction.

3. A hobber combining a head; means for feeding it in a given direction; a quick- 100 traverse for shifting it in opposite directions; a feed-lever; a traverse-lever, a member shiftable into a position preventing said quick-traverse from operating said head in said given direction but not in an opposite direction; and means for adjustably connecting said member and said head whereby 105 said member will be shifted into said preventing position only when said head has been moved a definite distance in said given direction.

4. A hobber combining a head; a quick- 110 traverse mechanism; a manual control normally available for causing said mechanism quickly to traverse said head in either of two opposite directions; and a member adjustably mounted on said head and adapted 115 when adjacent a predetermined zone to prevent said control from being so actuated as to cause said head to enter said zone at a quick traverse rate, but not to prevent it from retreating rapidly from said zone. 120

5. A hobber combining a head; feed- 125 mechanism for feeding it in but one direction, a traverse-mechanism for shifting said head rapidly in either of two opposite directions; a hand-lever for manually determining the action of said traverse-mechanism; manual means normally available for causing said feed-mechanism to feed said head; and an interlock for locking said manual means against being manipulated to start 130

said feed-mechanism while said traverse-mechanism is operating either forwardly or reversely.

6. A hobber combining a head; means for feeding it in a given direction; a quick-traverse for shifting it in opposite directions; a feed-lever; a traverse-lever; an interlock for throwing the former out when the latter is in; a member shiftable into a position preventing said quick-traverse from operating said head in said given direction but not in an opposite direction; and means for adjustably connecting said member and said head whereby said member will be shifted into said preventing position only when said head has been moved a definite distance in said given direction.

7. A hobber combining a head; a quick-traverse mechanism; a manual control normally available for causing said mechanism quickly to traverse said head in either of two opposite directions; and a cam having a bevel and a flat, the flat being adapted when said head has entered a predetermined zone to prevent said control from being so actuated as to cause said head to advance at a quick traverse rate, and said bevel being adapted to operate said control if set to produce an advance quick-traverse.

8. A hobber combining a head; means for feeding it in a given direction; a quick-traverse for shifting it in opposite directions; a feed-lever; a traverse-lever; and a cam having a bevel and a flat for shifting and then holding the traverse lever in a position preventing said quick-traverse from operating said head in said given direction but not in an opposite direction.

9. A hobber combining a head; means for feeding it in a given direction; a quick-traverse for shifting it in opposite directions; a feed lever shiftable into a neutral or a single operative position; a traverse lever shiftable into a neutral or into either of two operative positions; an interlock for compelling said feed lever to occupy its neutral position whenever the traverse lever is in either of said two operative positions; a yieldable detent for normally holding said feed lever from returning to its operative position; and mechanism in part mounted on said head and operative (a) at a selected station to shift said traverse lever from its one operative position into its neutral position, (b) thereafter to prevent a return of said lever but not to prevent it from being shifted into its other operative position.

10. In a hobbing machine, means for supporting the cutter and the work in a variable relation; quick-traverse mechanism for quickly varying said relation; feed mechanism for slowly varying said relation; and an interlock for enabling said quick-traverse mechanism to be operated reversely during any relation between the cutter and the work

and to be operated forwardly at any time other than when the cutter is in tooling relation with the work.

11. In a hobbing-machine, a feed mechanism; a quick-traverse mechanism; and means for limiting the extent of operation of the latter, said latter being constructed to permit the operation of the feed mechanism after the quick traverse mechanism has ceased to function and to prevent the latter from being put into other than reverse operation after the feed mechanism has been put into forward operation.

12. A hobbing-machine combining a quick-traverse mechanism; control means for causing it to function forwardly, idly or reversely; and an auxiliary check device necessitating an abnormal manual operation as a condition precedent to such a setting of said control as will cause the quick-traverse mechanism to function forwardly.

13. In a hobbing machine, selectively available mechanisms comprising a forwardly and reversely acting quick-traverse mechanism, and a feed-mechanism operable in but one direction; and means for automatically rendering the latter ineffective when the former is put into operation.

14. In a hobbing-machine, a quick-traverse mechanism; a manual control adapted to cause it to operate forwardly; a check device necessitating a preliminary manual manipulation before said control can be thus set; and a positively acting instrumentality for restoring said control to an initial position as soon as said quick-traverse mechanism has attained a predetermined station in its forward operation.

15. In a hobbing-machine, means for supporting the cutter and the work in a variable relation; quick-traverse mechanism for quickly varying said relation; feed mechanism for slowly varying said relation; and a control system adapted to be manually and automatically operated, 1st manually to start the quick-traverse forwardly, 2nd automatically to stop it when the cutter is about to perform a tooling operation, 3rd manually to start the feed mechanism whenever the cutter is to perform a tooling operation, 4th automatically to stop the feed mechanism when the cutter has performed its operation, 5th manually to start the quick-traverse reversely, and 6th automatically to arrest the return operation of the quick-traverse mechanism at a predetermined point.

16. In a hobbing-machine, means for supporting the cutter and the work in a variable relation; quick-traverse mechanism for quickly varying said relation; feed mechanism for slowly varying said relation; an interlock for enabling said quick-traverse mechanism to be operated reversely during any relation between the cutter and the work

- work and to be operated forwardly at any time other than when the cutter is in tooling relation with the work; and a check-device necessitating a preliminary extra manual manipulation before said quick-traverse mechanism can be operated forwardly. 5
17. In a hobbing-machine, a feed mechanism; a quick-traverse mechanism; two independent parts requiring individual manual manipulation to render said quick-traverse mechanism forwardly operative; and means for limiting the extent of forward operation of the latter, said latter being constructed to permit the forward operation of the feed mechanism after the quick-traverse mechanism has ceased to function and to prevent the latter from being put into other than reverse operation after the feed 15 mechanism has been put into forward operation. 20
18. A hobbing-machine combining a quick-traverse mechanism; control means for causing it to function forwardly, idly or reversely; an auxiliary check device necessitating an abnormal manual operation as a condition precedent to such a setting of said control as will cause the quick-traverse mechanism to function forwardly; and manual means adapted at any time to cause said quick-traverse mechanism to function reversely. 25
19. In a hobbing-machine, a quick-traverse mechanism; a manual control adapted to cause it to operate forwardly; a check device necessitating a preliminary manual manipulation before said control can be thus set; a positively acting instrumentality for restoring said control to an idle position as soon as said quick-traverse mechanism has attained a predetermined station in its forward operation; and manual means for causing said quick-traverse to function reversely at any time within the limits of its full scope 40 of operation. 45
20. In a hobbing machine, the combination of mechanism for synchronously rotating and relatively translating the work and the cutter spindles, of means for effecting said translation either at selective relatively slow positive rates or at a non-selective quick-traverse impositive rate forwardly or reversely. 50
21. A hobbing-machine combining a shiftable stanchion; a cutter-head slidable thereon; an intermediate transmission; a first clutch (r') to slowly drive it; a second clutch (Q^e) to rapidly drive it; an interlock inhibiting the simultaneous engagement of both of said clutches; a third clutch (S^e) for shifting said stanchion; a fourth clutch (F') for sliding said cutter-head, said four clutches being included in the transmission system between the main-shaft, the shiftable stanchion and the cutter-head; and an interlock preventing simultaneous engagement of said last two clutches. 55
22. A hobbing machine combining mechanism for relatively translating the work and the cutter spindles; alternatively available means for effecting said translation either at selective relatively slow positive rates or at a non-selective quick-traverse impositive rate forwardly or reversely; and independent mechanism for synchronously rotating said spindles. 60
23. A hobbing-machine combining a shiftable stanchion; a cutter-head slidable thereon; an intermediate transmission; a first clutch (r') to slowly drive it at selectively available feeding rates; a second clutch (Q^e) to rapidly drive it but impositively at a constant rate; an interlock inhibiting the simultaneous engagement of both of said clutches; a third clutch (S^e) deriving motion from said intermediate transmission shifting said stanchion; a fourth clutch (F') also deriving motion from it for sliding said cutter-head, said four clutches being included in the transmission system between the main-shaft, the shiftable stanchion and the cutter-head; an interlock preventing simultaneous engagement of said last two clutches; and a transmission system unaffected by any of said clutches for conveying motion to rotate relatively the cutter and the work. 65
24. A hobber combining a head; feed-mechanism available for feeding it in but one direction; a traverse-mechanism for shifting said head rapidly in either of two opposite directions; a manual control for starting said traverse mechanism and for determining the direction of its action; and means operable by said manual control for automatically rendering said feed-mechanism impotent when said manual control is manipulated to start said traverse-mechanism either forwardly or reversely. 100
- In witness whereof, I hereunto subscribe my name.
